UNITED STATES PATENT OFFICE.

HARRY E. ROSE, OF NEW YORK, N. Y.

AEROPLANE.

1,371,815.

Specification of Letters Patent. Patented Mar. 15, 1921.

Application filed November 14, 1918, Serial No. 262,521. Renewed November 16, 1920. Serial No. 424,508.

To all whom it may concern:

Be it known that I, HARRY E. ROSE, a citizen of the United States, and a resident of the city of New York, College Point, borough 5 of Queens, in the county of Queens and State of New York, have invented a new and improved Aeroplane, of which the following is a full, clear, and exact description.

An object of my invention is to provide 10 for the foot control of the steering rudder, lift rudder and ailerons of an aeroplane, thereby enabling the pilot of the machine to have his hands free for any emergency, or auxiliary duties he may undertake; a more 15 specific object being to coöperate in foot-controlled mechanisms with the usual hand lever, thereby permitting of certain of the controlling operations being carried out through the medium of the hand lever if 20 desired by the pilot. The dual foot and "stick" control thus give an increased margin of safety, having in view the possibility of injury to the pilot's arms and legs or injury to either the foot-control or hand-control 25 elements.

A further important object of the invention is to utilize the bodily movement of a foot bar for effecting the movements of two 30 of the three controlling mechanisms pertaining respectively to the steering rudder, lift rudder, and ailerons, and to provide a pedal mechanism controlling the third of said movements and operative independently of the other two mechanisms while coöordinated 35 with the latter.

An object of the invention, also, is to provide means for maintaining the pedals disposed at opposite sides of the foot board, in parallel relation and in lines running substantially fore and aft, notwithstanding the 40 turning movement of the foot board in its own plane or the vertical rocking thereof to effect two of the three controlling actions.

The said objects, and others as will appear, 45 are attained in the manner hereinafter explained. Reference is to be had to the accompanying drawings forming part of this specification, it being understood that the drawings are merely illustrative of one example of the invention.

Figure 1 is a diagrammatic perspective view given to show the connections between my controlling mechanisms and the steering rudder, lift rudder and ailerons.

Fig. 2 is a plan view of my improved mechanism.

Fig. 3 is a longitudinal vertical section on the line 3—3 of Fig. 2.

Fig. 4 is a rear end view of said mechanism, the hand-control elements being 60 omitted in the interest of clearness.

Fig. 5 is a detail in longitudinal vertical section showing the manner of supporting the heel plates associated with the pedals.

Fig. 6 is a diagrammatic plan view of the 65 mechanism, certain features being omitted.

Fig. 7 is a diagrammatic perspective view omitting certain features shown in Fig. 6 and including certain elements omitted from Fig. 6. 70

It will be understood that the movements of the three controlling mechanisms constituting my foot control may connect respectively with either of the elements to be controlled, that is to say, with the steering 75 rudder, with the lift rudder, or with the ailerons. For the purpose of illustration I have shown the ailerons controlled by a vertical rocking or sidewise tilting of the footboard and have shown the pivotal movement of the footboard in its own plane controlling the lift rudder, while the steering rudder is controlled by the vertical rocking of pedals forming part of my improved foot control. 80

In carrying out my invention in accordance with the illustrated example, a footboard 10 is provided and pivoted centrally by an approximately vertical bolt 11, or the like, in the forked end 12 of a rock shaft 13 90 extending longitudinally of the machine, said shaft turning in suitable bearings 14 and 15 on standards 16 and 17 rising from a base 18 secured to the body A of the machine. The turning of the shaft 13 through an angle effects control of the ailerons B' here shown associated with the planes B of a biplane. In the illustrated form said shaft 13 has a grooved wheel 19 thereon at the rear end on which cables 20 wind and extend laterally in opposite directions to a suitable connection with the respective lower ailerons B' of the plane shown, the upper and lower ailerons having any approved interconnections E and E', as conventionally shown. With the described arrangement, either end 100 of the footboard 10 may be depressed to turn the shaft 13 through an angle for actuating the ailerons B' through the connections 20 in the well known manner. 105

The footboard 10 may turn through an angle in its own plane about the vertical 110

bolt 11 as a center, and in the illustrated form connections are made between said footboard at opposite sides of its pivotal center 11 and with the lift rudder D by 5 cables 21, said cables being connected with eyes 22, or the like, on the rear edge of the footboard and extending from said eyes in pairs to the respective upper and lower arms F on the shaft G of said lift rudder. Thus, 10 a turning of the footboard about the pivot 11 in one direction will throw the lift rudder B upwardly, while a reverse turning movement of the footboard in its plane about the pivot 11 will impart reverse movement to the lift rudder. It will thus be seen 15 that the two different movements of the footboard 10, the one a vertical rocking movement and the other a horizontal movement, effects respectively the control of the 20 ailerons and the lift rudder.

In order to coöperate my foot-control mechanism with the ordinary "stick" control, as it is termed, I provide a vertical hand lever 23 which is made rigid with a 25 horizontal shaft 24 turning in a transverse bearing 25 in the shaft 13 or otherwise arranged so that the lever 23 and the transverse shaft 24 may have a forward and back rocking movement relative to the shaft 30 13, while at the same time a lateral vibration of the lever 23 will rock the shaft 13 either to the right or to the left, as desired. Vibration of the lever 23 forward and back is caused to give a turning movement to the 35 footboard 10 in its own plane about the pivot 11, for which purpose oppositely-directed crank arms 26 are provided on the ends of the shaft 24, the arm at one end extending upwardly from said shaft 24 40 and the crank arm at the opposite end extending downwardly, said crank arms being connected by links or connecting rods 27 with hooks 28, or the like, on the rear edge of the footboard 10 at opposite sides of its 45 pivotal center 11; thus, the hand lever may be employed to impart the vertical rocking movement to the footboard for controlling, in the illustrated arrangement, the ailerons B', while the forward and back vibration 50 of the lever through connecting rods 27 and the footboard 10 control the lift rudder D. Thus, the pilot, if he utilizes the foot control for the ailerons and lift rudder, will have his hands free for any other duties he 55 may wish to perform; and in the event of injury to the pilot's legs, for example, the hand lever may be utilized, or vice versa.

The third element to be controlled, to wit, the steering rudder is in the present example 60 of my invention controlled through the medium of pedals, designated by the numeral 29, disposed respectively adjacent to the opposite ends of the footboard 10, each pedal having a suitable toe strap at the 65 front end, as at 30. The rear ends of the

pedals 29 are secured to the outer ends of shaft sections 31 turning in suitable bearings 32 on the footboard 10, and on the adjacent inner ends of said shaft sections are provided lever arms 33 on the respective sections, said lever arms terminating in heads 34 having eyes 34^a, or the like, for the connection of cables 35, which are connected at one end with the respective arms 33 and extend therefrom to a connection with the 70 lever arms H on the shaft I of the steering rudder J. The shaft sections 31 and their arms move oppositely, so that as one arm 33 swings upwardly, the other arm 33 will swing downwardly to give corresponding 75 movements to the cables 35 connecting with the respective lever arms H, for which purpose the shaft sections 31 have bevel pinions 36 thereon meshing with sectors 37 on a gear element or disk 38 loose on the vertical 80 pivot 11, the arrangement being such that a rocking movement imparted to one shaft section 31 will give a reverse rocking movement to the opposite shaft section 31 and its 85 pedal 29. In order to maintain the pedals 90 29 parallel, or substantially so, with the longitudinal axis of the machine, the two lever arms 33 are constrained to move vertically in a definite path in rocking, for which purpose the said lever arms 33 extend through slots 39 in an arcuate guide 40 formed on a base plate 41, secured in the present example by the pivot bolt 11. Also, the lever arms 33 are connected with the pedals 29 by rods 42 parallel with the 95 shafts 31, said rods 42 being each pivoted at one end, as at 43, to a lever arm 33 and pivoted at its opposite end, as at 44, to a 100 pedal 29. Thus, the pedals are maintained in parallelism with the lever arms 33 and 105 with the definite vertical path of the movement of the latter. The described arrangement is provided to maintain the effective 110 positions of the pedals for direct up and down movement for rocking the shaft sections 33, the fore and aft positions being maintained notwithstanding the movement of the footboard 10 about its pivot 11. It will be observed that the connection between the pedals 29 and the shaft sections 115 31 is by pivots 45.

Heel plates 46 are associated with the 120 pedals but are independent of the latter. I provide for maintaining the relative positions of the heel plates and pedals regardless of movements of the footboard 10, for which purpose said heel plates are arranged to rock vertically, the hinge straps 47 thereon in the present example loosely embracing T heads 48, the shanks 48^a of which are 125 secured in standards 49 on the ends of a crossbar 51, said standards being pivoted as at 50 to said crossbar and the latter being mounted centrally for vertical pivotal movement by reason of a transverse pivot 130

52 connecting said crossbar to a short standard 53 adapted to turn in a step bearing 54 on the base 18 or on the fixed support. The standards 49 have connection with the ends 5 of the footboard 10 to permit the standards to rock laterally. The connection may be produced as shown by lateral studs 49^a on the standards 49 engaged by hinge straps 49^b embracing said studs and secured to the 10 footboard. With the described detail arrangement it will be readily understood that the pedals may be operated to control the steering rudder J through the cables 35 irrespective of the position or movements of 15 the footboard 10 in the control by the latter of the other two controlling elements, that is to say, the ailerons B' and lift rudder D.

I would here mention that I have referred in the foregoing to the ailerons as such 20 merely as an example of usual stabilizing means, and have referred to the lift rudder as such merely as an example of elevating means.

In conclusion, I would state that while 25 the illustrated example constitutes a practical embodiment of my invention, I do not limit myself strictly to the mechanical details herein illustrated, since, manifestly, the same can be considerably varied without departure from the spirit of the invention as defined in the appended claims.

I claim:

1. A flying machine having stabilizing means, lifting means and steering means; 35 together with foot operated controlling mechanism for said means, said controlling mechanism including a foot-bar having connection with two of said means and optionally movable to effect control of either of 40 said two means, and pedals optionally operative to effect control of the third of said means.

2. In a flying machine having stabilizing means, lifting means and steering means, a 45 horizontal foot - operated element tiltable laterally in a vertical plane to effect control of one of said means and adapted to be optionally turned through an angle in its

own plane to effect control of another of said means, pedals on said foot-operated element and vibratable vertically to effect control of the third of said means independently of movements of said foot element; together with means to maintain said pedals parallel with each other and with the line 55 of flight regardless of the movements of said foot element.

3. In a flying machine, controllable elements, and controlling means therefor, including a foot-operated member pivoted to turn in its own plane to control one of said elements and tiltable vertically to control another of said elements, a hand lever vibratable in two planes at right angles to each other, connections between the hand 65 lever and said foot-operated member to turn the latter by the vibration of the hand lever in one plane, and means operable by the vibration of the hand lever in the other of said planes or by the tilting of the foot-operated member to control the other of said elements.

4. In a flying machine, a controllable element and controlling means therefor including pedals, connections between the pedals 75 and said controllable element, heel plates for each pedal and separate therefrom, and means independent of the pedals and mounting said heel plates for universal movement.

5. In a flying machine, a controllable element, and controlling means therefor including pedals vibratable vertically, connections between said pedals and said element to control the latter, a foot bar pivoted to turn in its own plane, means pivotally 85 mounting said pedals on the foot bar to permit relative vertical movement of the pedals, means to maintain the pedals parallel in the turning of the foot bar, heel plates for the pedals and separate therefrom, and 90 means mounting said heel plates to permit vertical rocking of and lateral turning of the heel plates relatively to the pedals and foot board.

HARRY E. ROSE.
